UNITED STATES PATENT OFFICE

93,000

DESIGN FOR A PHOTOGRAPH STAND

Richard H. Becks, Chicago, Ill.

Application May 23, 1934, Serial No. 51,893

Term of patent 3½ years

To all whom it may concern:

Be it known that I, RICHARD H. BECKS, a citizen of the United States of America, residing at Chicago, Cook County, State of Illinois, have invented a new, original, and ornamental Design for a Photograph Stand, of which the following is a specification, reference being had to the accompanying drawing, forming a part thereof.

Figure 2 is a top plan view of the stand with the two halves thereof slightly inclined to each other for supporting the same in upright position.

I claim:

The ornamental design for a photograph stand, substantially as shown and described.

RICHARD H. BECKS.
